UNITED STATES PATENT OFFICE.

JAMES W. DAVIS, OF ENTERPRISE, KANSAS.

HEATING-DRUM.

SPECIFICATION forming part of Letters Patent No. 349,695, dated September 28, 1886.

Application filed January 14, 1886. Serial No. 188,568. (No model.)

To all whom it may concern:

Be it known that I, JAMES W. DAVIS, a citizen of the United States of America, residing at Enterprise, in the county of Dickinson and 5 State of Kansas, have invented certain new and useful Improvements in Heating-Drums; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 My invention relates to certain new and useful improvements in heating-drums which are adapted to be applied between the joints of a stove-pipe so as to utilize the heat which would otherwise pass into the flue; and my invention 20 consists in the construction and combination of the parts, as will be hereinafter fully set forth, and specifically pointed out in the claims.

In the accompanying drawings, which illustrate my invention, Figure 1 is a perspective 25 view of the exterior of my improvement. Fig. 2 is a vertical sectional view. Fig. 3 is a transverse section. Fig. 4 is a side view, partly broken away to show the interior construction. Fig. 5 is a plan view of the bottom of the drum. 30 Fig. 6 is a detail perspective view. Fig. 7 is a detail section view illustrating a modified manner of connecting the drum and pipe.

A refers to the drum or cylinder, which is of a greater diameter than the stove-pipe to which 35 it is applied, and said drum or cylinder is provided with central openings, adjacent to which are attached collars *a*, to which is secured, by means of rivets *a'*, the upper section of the pipe *A'*. The lower section of pipe, *A''*, is connected to the opposite head of the drum in the same manner. The heads of the drum *B* and *B'* are attached to the cylinder in the usual manner.

C refers to the inside pipe, which is provided 45 above and below its center with openings *c* and *c'*, said openings being located on a line with each other, and a damper, *D*, is pivotally secured at the center portion of this interior pipe, and has a handle, *d*, which extends from 50 said damper to the outside of the drum *A*.

E refers to a continuous partition-plate,

which extends from the upper end of the drum downwardly and near the center of the same, after which it is bent at right angles, so as to cross the drum horizontally in front of the pipe 55 *C*, and when said partition reaches the opposite side of said pipe it is bent downwardly until it reaches the opposite end of the drum upon which it rests. The vertical portion of this partition plate adjacent to the center pipe, 60 *C*, is secured thereto by rivets *e* which serve to hold the same securely in place.

By the construction hereinbefore described, it will be noted that when the damper is turned horizontally, as shown in Fig. 2, the heat and 65 products of combustion will enter the center pipe and pass through the opening *c'* therein, and will from thence pass around between the drum and exterior of the pipe *C* until it reaches the opening *c* in the pipe, through which it 70 will pass to the flue. By causing the products of combustion to take this circuitous course the heat will be utilized and very little pass up the flue and be wasted. When it is desired that the products of combustion pass directly 75 to the flue, the damper can be turned vertically so as to form no obstruction in the pipe *C*, in which case the heat will pass directly to the flue.

F refers to a cleaner or scraper, which is 80 placed within the drum, and normally rests upon the bottom thereof, said cleaner or scraper extending partially around the inner pipe, and the same has attached thereto a handle, *f*, which extends upwardly and out of the upper 85 top of the drum *B*. By moving this handle up and down the soot or other accumulations will be loosened from the side walls of the pipe and may be removed from the drum through an opening, *g*, in the bottom thereof, said opening being adapted to be covered by a pivoted 90 plate, *G*. The plate of the scraper or cleaner *F* is slightly spiral, so that the soot or other deposits which may fall thereon will be deposited near the opening *g*.

95 I claim—

1. In a heating-drum, the combination of an outer cylinder, *A*, an inner pipe, *C*, with openings *c* *c'* located on a line with each other, a damper located within the pipe *C* and between 100 said openings and provided with a handle, which extends beyond the outer cylinder, the

partition-plate E, having a vertical and a horizontal portion secured in position between the inner pipe and outer cylinder, said cylinder being provided at its lower head with an opening, g, and a covering-plate therefor, substantially as shown and for the purpose set forth.

2. In a heating-drum, the combination of an outer cylinder, an inner pipe attached thereto and provided with openings e and e', a damper, D, a partition extending from the upper end of the drum to its lower end and having a hori-

zontal portion between the upper and lower openings in the pipe and cleaner located in said drum concentric with said pipe, substantially as shown, and for the purpose set forth.

In testimony whereof I affix my signature in presence of two witnesses.

JAMES W. DAVIS.

Witnesses:

BYRON A. CALKINS,
H. M. WARNER.
